ABSTRACT

A toy launcher system is described, in which a lightweight projectile has an exterior surface symmetrically disposed about an imaginary longitudinal axis and is generally spool-shaped. The launcher is composed of a flexible shaft to which a flexible curled band is attached. The flexible curled band holds the projectile within its curvature. A user applying a bending force to the flexible shaft creates a spring force within the shaft. When the user removes the bending force, the spring force causes the flexible shaft to return to its rest state. As the flexible shaft returns to its rest state the band uncurls, thereby launching the projectile into flight.

MAGNUS EFFECT CYLINDRICAL PROJECTILE AND LAUNCHER

CLAIM TO PRIORITY

This application claims under 35 U.S.C. § 120, the benefit of the application Ser. No. 17/318,269, filed May 12, 2021, titled "Magnus Effect Cylindrical Projectile and Launcher" which is hereby incorporated by reference in its entirety.

BACKGROUND

An object in flight that spins around an axis that is not aligned with its direction of travel is subject to the Magnus Effect.

As an object in motion spins, the part of the object that is spinning into the oncoming air creates a small area of high pressure. Conversely, the part of the object that is spinning away from the oncoming air creates an area of low pressure. The areas of low pressure and high pressure produce a vectored force that can cause an object in flight to alter its direction. This movement is known as the Magnus Effect in fluid dynamics. The Magnus Effect enables cylindrical or tubular projectiles, when given sufficient linear and rotational velocities, to achieve lift and to move in a generally looping fashion.

In the toy industry, the Magnus Effect has been implemented to affect interesting projectile flight patterns. The problem with existing technologies is the complexity of use. For instance, mechanisms that require wrapping a projectile with an elastic cord or string require hand and eye coordination that is beyond the skillset of many children and adults. In addition, elastic cords or strings are not easily aligned in the center of such a projectile. As a consequence, the projectile can easily be launched off-balance, destroying the necessary aerodynamic conditions and ruining the desired looping effect.

BRIEF DESCRIPTION OF THE DRAWINGS

Certain illustrative embodiments illustrating organization and method of operation, together with objects and advantages may be best understood by reference detailed description that follows taken in conjunction with the accompanying drawings in which:

FIG. 1 is a perspective view of a projectile consistent with certain aspects of the present invention;

FIG. 2 is a side view of the projectile of FIG. 1 showing the forces that act upon the projectile in flight consistent with certain aspects of the present invention;

FIG. 3 is an isometric view of a generally spool-shaped projectile consistent with certain aspects of the present invention;

FIG. 4 is front view of the generally spool-shaped projectile of FIG. 3 consistent with certain aspects of the present invention;

FIG. 5 is a side view of the generally spool-shaped projectile of FIG. 3 consistent with certain aspects of the present invention;

FIG. 6 is an isometric view of a launch device embodiment with band uncurled consistent with certain aspects of the present invention;

FIG. 7 is a side view of the launch device embodiment of FIG. 6 consistent with certain aspects of the present invention;

FIG. 8 is a rear view of the launch device embodiment of FIG. 6 consistent with certain aspects of the present invention;

FIG. 9 is an isometric view of the launch device embodiment with band curled consistent with certain aspects of the present invention;

FIG. 10 is an isometric view of the assembly consisting of the generally spool-shaped projectile of FIG. 3 loaded onto the launch device embodiment of FIG. 9 consistent with certain aspects of the present invention;

FIG. 11 is a side view of the assembly of FIG. 10 consistent with certain aspects of the present invention;

FIG. 12 is a front view of the assembly of FIG. 10 consistent with certain aspects of the present invention;

FIG. 13 is an in-use view of the assembly of FIG. 10 consistent with certain aspects of the present invention;

FIG. 14 is a side view of the handle of a launch device embodiment consistent with certain aspects of the present invention;

FIG. 15A is an isometric view of a second launch device embodiment consistent with certain aspects of the present invention;

FIG. 15B is an isometric view of a second assembly consistent with certain aspects of the present invention; and

FIG. 16 is an in-use view of the second assembly of FIG. 15B consistent with certain embodiments of the present invention.

DETAILED DESCRIPTION

While this invention is susceptible of embodiment in many different forms, there is shown in the drawings and will herein be described in detail specific embodiments, with the understanding that the present disclosure of such embodiments is to be considered as an example of the principles and not intended to limit the invention to the specific embodiments shown and described. In the description below, like reference numerals are used to describe the same, similar or corresponding parts in the several views of the drawings.

The terms "a" or "an", as used herein, are defined as one, or more than one. The term "plurality", as used herein, is defined as two, or more than two. The term "another", as used herein, is defined as at least a second or more. The terms "including" and/or "having", as used herein, are defined as comprising (i.e., open language). The term "coupled", as used herein, is defined as connected, although not necessarily directly, and not necessarily mechanically.

Reference throughout this document to "one embodiment", "certain embodiments", "an exemplary embodiment" or similar terms means that a particular feature, structure, or characteristic described in connection with the embodiment is included in at least one embodiment of the present invention. Thus, the appearances of such phrases or in various places throughout this specification are not necessarily all referring to the same embodiment. Furthermore,

the particular features, structures, or characteristics may be combined in any suitable manner in one or more embodiments without limitation.

The present invention is a toy projectile and launcher system. The projectile is cylindrical in shape and lightweight. The projectile has an exterior surface that is symmetrically disposed about an imaginary longitudinal axis.

Although the present invention projectile and launcher can be embodied in many ways, only a few embodiments of the invention are illustrated and described. These embodiments are selected in order to set forth some of the best modes contemplated for the invention. The illustrated embodiments, however, are merely exemplary and should not be considered limitations when interpreting the scope of the appended claims.

In an embodiment, the present invention is a toy cylinder and launcher system characterized by a cylindrical projectile and a shaft-shaped launcher. The lightweight cylindrical projectile has an exterior surface symmetrically disposed about an imaginary longitudinal axis and in an embodiment is generally spool-shaped. The launcher is a shaft to which a flexible curled band is attached. The flexible curled band holds the projectile snugly within its curvature. When the launcher is rotated by a user using a general throwing motion the band uncurls, thereby launching the projectile into flight. The band may be made of any number of materials including, by way of non-limiting example, steel or other metal, plastic, fabric, and/or rubber. The band may be covered with one or more materials to enhance tactility, safety, and/or aesthetic appeal. Such cover materials may be any number of materials including, by way of non-limiting example, rubber, cloth, tape and/or paper.

In an embodiment, the present invention is a toy launcher system characterized by a cylindrical projectile having an exterior surface that is symmetrically disposed about an imaginary longitudinal axis and a launcher having a band attached to a shaft at the proximal end of said band. The band is flexible and holds said cylindrical projectile through circumferential application of a normal force. The band is flexibly able to curl into a circular shape that is capable of holding the cylindrical projectile snugly within the circumference defined by the circular shape. A user launches the cylindrical projectile through application of a linear motive force that acts upon the cylindrical projectile at a substantially right angle to said imaginary longitudinal axis. When the user provides such motive force manually, by application of a general throwing motion, or through application of a spring element or pneumatic piston element, the band uncurls and imparts to the cylindrical projectile both a linear velocity and a rotational velocity. The combination of said linear motive force and said normal force, imparting linear and rotational velocities, enables lift in the cylindrical projectile. This lift is in a direction perpendicular to said imaginary longitudinal axis. The cylindrical projectile, once airborne, proceeds to move along a generally looping path.

In an embodiment, the present invention is a toy cylinder and launcher system characterized by a cylindrical projectile and a shaft-shaped launcher, wherein at least a portion of the shaft-shaped launcher is capable of serving as a spring element. In an embodiment, the spring element is capable of being loaded through application of spring compression and/or tension. The spring-loaded portion and/or portions of the launcher system may connect two or more rigid, separately articulable segments of the shaft-shaped launcher. The spring-loaded portion of the launcher system may run the full length of the shaft-shaped launcher and may make use of a restoring force inherent to the constituent material of the

shaft-shaped launcher. By way of non-limiting example, the spring-loaded portion of the launcher system may be constructed of any semi-rigid linear stock capable of storing energy through being deformed by application of an outside force and tending to return to its original, non-deformed state upon removal of that outside force. By way of non-limiting example, such semi-rigid linear stock may be fiberglass, carbon fiber, plastic, and/or metal, among other materials.

10 In an embodiment, the spring-loaded portion of the launcher system may be characterized by a cantilevered shaft-shaped launcher subjected to a perpendicularly-applied bending force at the free end of the cantilever, where the bending force creates a spring force within the shaft-shaped launcher. In an embodiment, the created spring force is proportional to the bending force. When the bending force is removed, the shaft-shaped launcher rapidly returns to its resting state through unresisted material restoring force.

15 In an embodiment, the spring-loaded portion of the launcher system permits smooth, even and repeatable application of a bending force and smooth, even and repeatable activation of a restoring force.

20 In an embodiment, the present invention is a toy cylinder and launcher system characterized by a cylindrical projectile and a flexible, semi-rigid shaft-shaped launcher. The lightweight cylindrical projectile has an exterior surface symmetrically disposed about an imaginary longitudinal axis and in an embodiment is generally spool-shaped. The launcher may be a semi-rigid shaft capable of deformation within the elastic range of the shaft material. A flexible curled band may be attached to the launcher at the end of the band that is proximal to a user. The flexible curled band holds the projectile snugly within its curvature. When the launcher is subjected to a bending force, a proportional 25 spring force results in the launcher material. When the bending force is removed, the spring force tends to rapidly restore the launcher to its undeformed state, causing the band to uncurl and thereby launching the projectile into flight. The band may be made of any number of materials including, by way of non-limiting example, steel or other metal, plastic, fabric, and/or rubber. The band employs the semi-rigidity inherent to its constituent material. The band may be covered with one or more materials to enhance tactility, safety, and/or aesthetic appeal. Such cover materials 30 may be any number of materials including, by way of non-limiting example, rubber, cloth, tape and/or paper.

35 In an embodiment, the present invention is a toy launcher system, made up of a launcher; a cylindrical projectile having an exterior surface that is symmetrically disposed about an imaginary longitudinal axis; a metal and/or plastic band having an end proximal to a user; the metal and/or plastic band attached to said launcher at the end of said metal and/or plastic band proximal to a user, where the metal and/or plastic band holds said cylindrical projectile through 40 circumferential application of a normal force and enables secure holding of said cylindrical projectile to said launcher; launching said cylindrical projectile through application of a motive force, where said motive force acts upon said cylindrical projectile at a substantially right angle to said imaginary longitudinal axis; said motive force being provided by a spring-loaded element; said motive force and said normal force enabling lift in said cylindrical projectile in a direction perpendicular to said imaginary longitudinal axis. In an embodiment, the spring-loaded element is a semi-rigid shaft 45 temporarily deformed within the elastic range of the shaft.

50 In an embodiment, the present invention includes a container attached to or near the launcher, in which the cylinder

drical projectile may be caught after it is launched or stored when not in use. The container may be used to catch any other similar projectile, including, by way of non-limiting example, one or more cylindrical projectiles launched from launchers other than the one to which the container is attached.

Referring to FIG. 1 and FIG. 2, a Standard Projectile 10 is shown. The Standard Projectile 10 has a Cylindrical Body 12 with a length L1 and a diameter D1. The Cylindrical Body 12 may be mostly hollow or composed of a light-weight substance, such as by way of non-limiting example, foam or foam rubber, in order to minimize weight. The length L1 is preferably at least three times as long as the diameter D1 is wide. The Cylindrical Body 12 is symmetrically formed about an imaginary long axis 14 that runs along its length L1 through the center of the Standard Projectile 10. The Cylindrical Body 12 can be fabricated from any suitably durable and lightweight material, including by way of non-limiting example, plastic, laminated paper, foam or foam rubber, among other materials.

In FIG. 2, the Standard Projectile 10 is shown in flight, wherein it is traveling in the primary direction of arrow 15. As the Standard Projectile 10 is traveling in the direction of arrow 15, it is also spinning about its long axis 14 in the direction of arrow 17. The spinning of the Standard Projectile 10 moves some of the air near the Exterior Surface 16 of the Standard Projectile 10. This air moved by the Standard Projectile 10 creates a slight high pressure under the Standard Projectile 10 and a slight low pressure above the Standard Projectile 10. The high pressure and low pressure act upon the Standard Projectile 10 and create a vectored Magnus force in the direction of arrow 19. The Magnus force is generally perpendicular to the forward direction of flight. The Magnus force therefore initially creates an upward force that inclines the direction of flight. As the Magnus force continues, it tends to cause the Standard Projectile 10 to fly vertically in a circle, therein producing a loop in flight. As such, the Magnus force tends to cause the Standard Projectile 10 to loop and return to its point of origin.

Turning now to FIG. 3, an isometric view of a generally spool-shaped projectile consistent with certain aspects of the present invention is shown. The generally Spool-Shaped Projectile 30 is composed of Cylindrical Body 12 and End Plates 34. End Plates 34 are composed of thin, lightweight, semi-rigid material such as but not limited to paper, plastic, foam, or foam rubber. In an embodiment End Plates 34 are about one-sixteenth inch in thickness. End Plates 34 are roughly circular in shape, with an outside diameter greater than the outside diameter of Cylindrical Body 12. In an embodiment the length of Cylindrical Body 12 is about four times the diameter of Cylindrical Body 12. While the specific measurements and shapes described herein refer to a particular embodiment of the invention, each measurement and shape can be varied without changing the nature of the invention.

Turning now to FIG. 4, a front view of the generally spool-shaped projectile of FIG. 3 consistent with certain aspects of the present invention is shown. End Plates 34 are chemically or mechanically attached to Cylindrical Body 12.

Turning now to FIG. 5, a side view of the generally spool-shaped projectile of FIG. 3 consistent with certain aspects of the present invention is shown, such that only one End Plate 34 is visible.

Turning now to FIG. 6, an isometric view of the launch device embodiment with band uncurled consistent with certain aspects of the present invention is shown. Launch

device 60 includes Shaft 62 and Flexible Curled Band 64. In an embodiment, Flexible Curled Band 64 may be, by way of non-limiting example, a steel ribbon or bi-stable steel ribbon. Other materials may be employed for Flexible Curled Band 64 such as, but not limited to, plastic, fabric, rubber, and paperboard. Flexible Curled Band 64 may be entirely covered in a safe, durable, flexible, and decorative material such as, by way of non-limiting example, silicone rubber. Among other non-limiting materials for the covering are plastic film, plastic tape, paper tape, and fabric. In an embodiment, such covering may increase the friction between the Flexible Curled Band 64 and any object against which it is placed. Flexible Curled Band 64 is secured to Shaft 62 at the proximal end of Flexible Curled Band 64, the other end of Flexible Curled Band 64 being free to curl inward upon itself in a generally concentric fashion. In an embodiment the length of the free end of Flexible Curled Band 64 is about equal to the outside circumference of the Cylindrical Body (not shown).

Turning now to FIG. 7, a side view of the launch device embodiment of FIG. 6 consistent with certain aspects of the present invention is shown. Shaft 62 tapers from end of Handle 74 to tip of Launchpad 76. In an embodiment Shaft 62 is generally S-shaped and measures about fifteen inches from the end of Handle 74 to tip of Launchpad 76. Launchpad 76 forms the portion of Shaft 62 from Main Bend 78 to the tip of Launchpad 76. In an embodiment, Main Bend 78 has an inside angle measurement of about 140 degrees. Flexible Curled Band 64 extends about from Main Bend 78 to the tip of Launchpad 76. While the specific measurements and shapes described herein refer to a particular embodiment of the invention, each measurement and shape can be varied without changing the nature of the invention.

Turning now to FIG. 8, a rear view of the launch device embodiment of FIG. 6 consistent with certain aspects of the present invention is shown. In the figure, only Shaft 62 is visible.

Turning now to FIG. 9, an isometric view of the launch device embodiment with band curled consistent with certain aspects of the present invention is shown. Flexible Curled Band 64 is chemically or mechanically attached to Shaft 62 at the proximal end of Flexible Curled Band 64.

Turning now to FIG. 10, an isometric view of the Assembly 1000 consisting of the generally spool-shaped projectile of FIG. 3 loaded onto the launch device embodiment of FIG. 9 consistent with certain aspects of the present invention is shown. Spool-Shaped Projectile 30 is shown with Flexible Curled Band 64 wrapped around it such that the free end of Flexible Curled Band 64 curls over the top of Spool-Shaped Projectile 30 and holds Spool-Shaped Projectile 30 against the front of Shaft 62.

Turning now to FIG. 11, a side view of the assembly of FIG. 10 consistent with certain aspects of the present invention is shown. Spool-Shaped Projectile 30 is shown held against the front of Shaft 62.

Turning now to FIG. 12, a front view of the assembly of FIG. 10 consistent with certain aspects of the present invention is shown. Spool-Shaped Projectile 30 is shown held against the front of Shaft 62 by Flexible Curled Band 64.

Turning now to FIG. 13, an in-use view of the assembly of FIG. 10 consistent with certain aspects of the present invention is shown. In an embodiment, User 1300 holds the assembly of FIG. 10 in one hand and moves the assembly with a general throwing motion, moving the assembly from First Position 1320 to Second Position 1321. In an embodiment, the thumb of the throwing arm of User 1300 lays along the surface of the Shaft 62 that is opposite to the surface of

the Shaft 62 upon which the Flexible Curled Band 64 is affixed (not shown). At First Position 1320, Flexible Curved Band 64 securely holds Spool-Shaped Projectile 30 within the space defined by its curvature. As User 1300 moves the assembly along Arc 1310 from First Position 1320 into Second Position 1321, forces caused by User's motion cause the Flexible Curved Band 64 to uncurl, generally imparting a Rapid Rotational Velocity 1314 to Spool-Shaped Projectile 30. User's motion also imparts to Spool-Shaped Projectile 30 a linear velocity while it is spinning. The forward projection away from User 1300 and the Rapid Rotational Velocity 1314 creates a Magnus force that launches Spool-Shaped Projectile 30 into flight. Spool-Shaped Projectile 30 tends to fly up and around in a Looping Flight Path 1312. Alternatively, Standard Projectile 10 may be substituted for Spool-Shaped Projectile 30 (not shown.)

Turning now to FIG. 14, a side view of the handle of a launch device embodiment consistent with certain aspects of the present invention is shown. At 1400, the thumb of the throwing arm of a user is lain along the rear of Shaft 62. The rear of Shaft 62 is the surface of Shaft 62 that is opposite to the surface of the Shaft 62 upon which the Flexible Curled Band (not shown) is affixed.

Turning now to FIG. 15A, an isometric view of a second launch device embodiment consistent with certain aspects of the present invention is shown. Second Launch Device 1500 is shown with Handle 1502, a rigid cylinder which in a non-limiting example may be made of wood, plastic, resin, metal, or any similarly rigid material. Handle 1502 is surmounted by Container 1501, where container 1501 is characterized by a Bottom Panel 1506 and a Cylindrical Wall 1504 together defining an open Cylindrical Void 1508. Flexible Shaft 1510 protrudes from Handle 1502, extends through open cylindrical void 1508, and rises through the imaginary plane that is co-planer with the top edge of Cylindrical Wall 1504. Flexible Shaft 1510 is capable of being spring-loaded through application of a spring compression and/or tension force, and in a non-limiting example may be made of fiberglass, carbon fiber, plastic, and/or metal. One end of Second Flexible Curled Band 1512 is attached to Flexible Shaft 1510; the other end of Second Flexible Curled Band 1512 is free to flex and move. In an embodiment, Second Flexible Curled Band 1512 may be any semi-rigid yet flexible material such as, by way of non-limiting example, metal, plastic, fabric, rubber, and paperboard.

Turning now to FIG. 15B, an isometric view of a Second Assembly consistent with certain aspects of the present invention is shown. Second Assembly 1503 is shown with Handle 1502, a rigid cylinder which in a non-limiting example may be made of wood, plastic, resin, metal, or any similarly rigid material. Handle 1502 is surmounted by Container 1501, where container 1501 is characterized by a Bottom Panel 1506 and a Cylindrical Wall 1504 together defining an open Cylindrical Void 1508. Flexible Shaft 1510 protrudes from Handle 1502, extends through open cylindrical void 1508, and rises through the imaginary plane bounded by the top edge of Cylindrical Wall 1504. Flexible Shaft 1510 is capable of being spring-loaded through application of a spring compression and/or tension force, and in

a non-limiting example may be made of fiberglass, carbon fiber, plastic, and/or metal. One end of Second Flexible Curled Band 1512 is attached to Flexible Shaft 1510; the other end of Second Flexible Curled Band 1512 is free to flex and move. Second Flexible Curled Band 1512 is shown wrapped around Second Spool-shaped Projectile 1514. Second Flexible Curled Band 1512 holds Second Spool-shaped Projectile 1514 securely by means of application of a circumferentially-applied normal force.

Turning now to FIG. 16, an in-use view of the Second Assembly of FIG. 15B consistent with certain embodiments of the present invention is shown. In an embodiment, User's Right Hand 1600 holds Handle 1502 while User's Left Hand 1601 bends Flexible Shaft 1510 into Bent Position 1602 through application of a pull force. When released by User's Left Hand 1601, Flexible Shaft 1510 returns to Rest Position 1604 through Second Arc 1608. Forces caused by the motion of Flexible Shaft 1510 cause the Second Flexible Curled Band 1512 to uncurl, generally imparting a Rapid Rotational Velocity 1612 to Second Spool-Shaped Projectile 1514. The motion of Flexible shaft 1510 also imparts to Second Spool-Shaped Projectile 1514 a linear velocity while it is spinning. The combination of the linear velocity and the Rapid Rotational Velocity 1612 creates a Magnus force that launches Second Spool-Shaped Projectile 1514 into flight. Second Spool-Shaped Projectile 1514 tends to fly up and around in a Looping Flight Path 1610. User may employ Container 1501 to catch Second Spool-shaped Projectile 1514.

While certain illustrative embodiments have been described, it is evident that many alternatives, modifications, permutations and variations will become apparent to those skilled in the art in light of the foregoing description.

I claim:

1. A toy launcher system, comprising:
a launcher;
a cylindrical projectile having an exterior surface that is symmetrically disposed about an imaginary longitudinal axis;
a metal and/or plastic band having an end proximal to a user;
the metal and/or plastic band attached to said launcher at the end of said metal and/or plastic band proximal to a user, where the metal and/or plastic band holds said cylindrical projectile through circumferential application of a normal force and enables secure holding of said cylindrical projectile to said launcher;
launching said cylindrical projectile through application of a motive force, where said motive force acts upon said cylindrical projectile at a substantially right angle to said imaginary longitudinal axis;
said motive force being provided by a flexible shaft spring-loaded with a restoring force when deformed within an elastic range of the shaft;
said motive force and said normal force enabling lift in said cylindrical projectile in a direction perpendicular to said imaginary longitudinal axis.
2. The system of claim 1, where said cylindrical projectile is spool shaped.
